Karl C. Augenstein, Cranston, R.I., assignor to Speidel Corporation, Providence, R.I., a corporation of Rhode Island

Application May 9, 1958, Serial No. 50,820

Term of patent 14 years

(Cl. D45—4)

FIG. 1

FIG. 2

FIG. 3

FIG. 4

Fig. 1 is a top plan view of an expansible link chain for a bracelet embodying my new design with the links in contracted position;

Fig. 2 is a view similar to Fig. 1 with the links in an expanded position, portions of the conventional appearing bottom links being visible between the expanded top links;

Fig. 3 is an enlarged top plan view of a single top link of the expansible chain; and

Fig. 4 is an edge elevational view looking from right to left at the link shown in Fig. 3.

I claim:

The ornamental design for an expansible link chain for a bracelet or similar article, substantially as shown and described.
